(57) **CLAIM**

The ornamental design for a generator body, as shown and described.

DESCRIPTION

FIG. 1 is a top, front and left side isometric view of a generator body showing my new design;

FIG. 2 is a top, front and right side isometric view thereof;

FIG. 3 is a top plan view thereof;

FIG. 4 is a right side elevation view thereof;

FIG. 5 is a left side elevation view thereof;

FIG. 6 is a front elevation view thereof; and,

FIG. 7 is a rear elevation view thereof.

The portions of the generator body shown in broken lines is for the purpose of showing environmental structure only and forms no part of the claim. Where broken lines abut a claimed surface it is understood that those broken lines represent an unclaimed boundary between claimed and unclaimed surfaces. None of the broken lines form any part of the claimed design.
